UNITED STATES PATENT OFFICE.

ALLEN DE VILBISS, JR., OF COLUMBUS, OHIO, ASSIGNOR OF TWO-THIRDS
TO WILLIAM T. WELLS AND JOHN F. PIXLEY, OF COLUMBUS, OHIO.

RECORDING-LOCK.

SPECIFICATION forming part of Letters Patent No. 735,034, dated July 28, 1903.

Application filed August 29, 1902. Serial No. 121,499. (No model.)

To all whom it may concern:

Be it known that I, ALLEN DE VILBISS, Jr., a citizen of the United States, and a resident of Columbus, Franklin county, State of Ohio, have invented certain new and useful Improvements in Recording-Locks; and my preferred manner of carrying out the invention is set forth in the following full, clear, and exact description, terminating with claims particularly specifying the novelty.

This invention relates to recorders, more especially to that class known as "workmen's time-operated recording-machines," such as are actuated by any one of several keys; and the object of the same is to produce a recording-lock which each time it is opened will furnish a correct record of the hour and minute when such opening occurred and a correct record of the key which was employed.

Experience has taught the proprietors of some establishments whose employees have keys of their own that on occasions some person possessing such a key may return after hours, enter the establishment with perhaps foul intent, remain therein for some time, and then depart, and heretofore the employer who may reside elsewhere has no means of knowing what has occurred unless he should later discover some of the results.

The object of the present invention is to devise a lock for the main or front door of the establishment which shall contain a recording mechanism of such construction that it will make a record of the time when such entry into the building was effected and the exact key which was used and will make another record when the lock was again opened to permit exit from the building, thus furnishing the employer with knowledge which will serve as a check upon those who should have his key. It is obvious that an almost endless combination of mechanisms can be employed for carrying out this general idea, and I desire it distinctly understood that the present specification and drawings are intended to set forth only one of many constructions and arrangements which might be used.

Herein I have employed broad terms, especially in the claims, and in the specification and drawings I have set forth specific-

ally the construction of the elements broadly covered by those terms merely in order to explain one form of each element and one arrangement of the whole which occurs to me at this time.

To this end the invention consists in a lock of any type which will answer, with which is combined and associated a recording mechanism of the type hereinafter set forth.

In the accompanying drawings, Figure I is a central longitudinal section of the lock with the bolt shot. Fig. II is a similar section with the bolt retracted, showing in dotted lines how the actuating-lever of the paper-feed is sprung over the key-bit. Fig. III is an elevation of the lock with the front plate removed, showing the bolt as shot and illustrating more particularly the key-indicator, which is located to this side of and does not appear in the two previous views. This figure also shows a modification of the paper-feed, which is perhaps a better construction than that elsewhere illustrated. Fig. IV is a transverse section on the line IV IV of Fig. III. Fig. V is a diagrammatic view illustrating the action of the key-bit on the key-indicator setting-lever.

The lock proper comprises a casing 1, having a keyhole 2, in which is intended to work a key having a shank 3 and a bit 4, as shown. The latter enters a notch 5 in the bolt 6, which in this case has a beveled front end 7 and is thrown normally forward by a spring 8, as usual in what are known as "spring-locks." It is not necessary to illustrate other features of the lock, and it will be clear that the latter need not necessarily be of the spring type. However, the term "bolt" used herein is intended to designate that part of the lock which engages with a keeper to lock the door closed.

The recording mechanism as a whole is actuated through the movement of the key, the latter in the present construction acting directly on certain parts and acting indirectly through the bolt on other parts, all as more fully described below; but it is the insertion and movement of the key in the lock which produces the record. In the present case the latter comprises a time-record and a key-record, the former indicating the

time when the key was used on each occasion of its use and the latter indicating which key was used. In the present instance the keys are differentiated from each other by slight differences in the radial lengths of their bits; but it will be understood that differences in the longitudinal lengths thereof or in the shape of the bits could be made use of to the same end. The recording mechanism as a whole comprises in the present instance a time-indicator, a key-indicator, an inker for both, a paper-roll from which a strip is drawn over both indicators by a paper-feed, and a printing mechanism, and these parts will now be described separately.

The time-indicator in the present instance comprises an hour-wheel 10 and a minute-wheel 11, connected by gearing 12 and so mounted that their upper faces stand flush beneath the paper. These wheels are of the drum type and have characters 13 on their peripheries. In the present case these are printing characters or type rising above the drum-faces; but they could be dies which would indent or puncture the record-strip described below. Preferably within the hour-wheel is located a clock mechanism adapted to be wound by the spindle 14, which mechanism is so arranged as to turn the minute-wheel one-twelfth of a revolution every five minutes and to turn the hour-wheel one-twelfth of a revolution every hour; but any arrangement will answer which will cause this time-indicator to have a movement (preferably intermittent) so that its uppermost characters shall constantly indicate the exact or approximate time.

The key-indicator herein shown comprises a wheel 20, also of the drum type and having characters 23 on its periphery, which may be letters or words, to indicate the various keys employed. This drum may well be mounted on the shaft of the larger time-wheel, and it may have a hub 21 with a roughened or notched periphery, against which presses the tip of a retaining-spring 22 for the purpose of steadyng the wheel while in use. Its hub, possibly at the other side of its body, may be provided with a pinion 24, engaged by a rack-bar 25, pivotally supported at one end of a lever 26, whose other end is pivoted in a bracket 27, the lever being drawn into normal position against a stop 28 by a spring 29. This lever stands in the present instance above the keyhole, as best seen in Fig. V, and along its lower edge it has an active face which is practically straight from 30 to 31, where it merges into a neutral face extending from 31 to 32 and struck on an arc corresponding substantially with that described by the outer end of the key-bit 4. As the key turns in the direction of the arrow in this view it first strikes the point 30, and as it travels to the point 31 it raises the setting-lever, which raises the rack-bar, which rotates the key-indicator and brings uppermost thereon a certain character corresponding

with the length of the key-bit and the height to which the active face was raised. Next the bit strikes the edge of the notch 5 in the bolt 6 and performs the work described below. Reaching the point 31, which has now been raised to the dotted lines, the bit travels around the neutral face of the lever 26 to the point 32. During this travel it does no work, and the retaining-spring 22 holds the key-indicator steady.

The inker 39 may be of any type; but in the present instance it is simply a roller mounted on a suitable bearing and faced with 8c felt or an equivalent cushion, which bears constantly on the characters of the wheels passing beneath it, the felt being moistened with ink from time to time. If the indicators are of the die form, which impress or cut the record-strips, the inker will be omitted.

The record-feed in the present instance comprises a drum 40, herein shown as drawing a strip of paper or the like off of a roll 42, which is held by a tension-spring 43, although this record might be cloth, metal, or anything suitable for receiving the impression of the characters on the indicators. Any suitable means may be employed for turning the drum. In Figs. I and II, I have shown a lever 44, having an actuating-pawl 45 engaging a ratchet 46 on the end of the drum (47 being a retaining-pawl) and the tip 48 of this lever stands in the path of the key-bit. By preference it has a spring-actuated knuckle-joint 49 where it is connected with the body of the lever, so as to permit the key to move in the other direction. The entire lever is of such a length and so pivoted that its tip slides off the key-bit, as shown in dotted lines 105 in Fig. II, just as the bit moves the bolt to make the impression, as described below. A slight modification of these features and a simpler construction is shown in Fig. III. Herein the actuating-pawl 450 is pivoted directly to the bolt 6 and is thrown up against the ratchet by a spring 490. The shape and length of this pawl must be such that the feed of the record will be accomplished and finished before the bolt has been moved sufficiently to do the printing, as described below.

The recorder in the present instance is a printing mechanism, because it employs a platen adapted to press a paper strip against type which have been inked; but it is clear 120 that this recorder could be a complementary die or a cushion or anything whose function was to impress or imprint the characters of the indicators on or into the record-strip. In fact, the face of the recorder could itself receive the imprint, so that the paper might be omitted. As shown herein, 50 is a platen carried by one end of an arm 51, which is intermediately pivoted, as at 52. Pivoted to the other end of this arm is a push-bar 53, herein shown as hanging therefrom and resting normally against a stop 54. This bar may have an antifriction device, such as a roller 55, at its lower end. Said end stands above

the lower extremity of a cam 56, rising from the bolt. It follows that when the latter is thrown inward the active face of the cam raises the push-bar, depresses the platen, and makes a record of those characters on the indicator which were at that moment uppermost, and as the bolt is again shot its lower end or heel swings the lower end of the push-bar outward, so that it drops back to the position shown and ready for subsequent use.

The indicators are herein shown as wheels, which form, I presume, is the preferred one, yet I do not limit myself to such a construction. It is clear that an independently-driven time-indicator will not be useful as an "indicator" without some printing mechanism used in conjunction unless mechanism be used to stop its rotation when the bolt is moved. Not only is this idea broadly old, but such a device could then indicate only one point of time, and subsequent employees might enter the building without making a record or giving any indication. It will also be clear that the key-indicator is not useful without the printing mechanism so long as the spring 29 is employed, which returns it to the starting-point after the withdrawal of the key; but by omitting this spring one indication (and only one) could be expressed without the use of the printing mechanism. Hence to make these wheels indicators in a true sense I may provide their side faces with letters or figures, as shown at 100 in Fig. III, and have openings 101 in the lock-casing, through which these can be seen. I lay no claim to this feature, however, but have described it to show one of a great variety of amplifications and modifications to which the broad idea of this invention is susceptible without departing from its spirit. I might add that it is not inconsistent with the invention to omit either indicator and use only the other, to use both, as shown, or to employ other indicators for other purposes when desired.

While I have described the invention as useful in the lock which closes the main door of an establishment, it is clear that the machine could be used as a workmen's time- record to check his arrival in the morning and his departure in the evening.

What I claim as new is—

1. In a recording-lock, the combination with a key-operated locking-bolt; of recording mechanism and means for actuating it through the movement of the key, said mechanism including a time-indicator and a key-indicator.

2. In a recording-lock, the combination with a key-operated locking-bolt; of recording mechanism including an independently-driven time-indicator, and a recorder coöperating therewith and moved by the bolt.

3. In a recording-lock, the combination with a key-operated locking-bolt; of recording mechanism including an independently-driven time-indicator, a recorder coöperating

therewith and moved by the bolt, a record-feed, and means for actuating it through the movements of the key.

70

4. In a recording-lock, the combination with a key-operated locking-bolt; of recording mechanism including an independently-driven time-indicator, and a printing mechanism and paper-feed, both moved by the bolt.

5. In a recording-lock, the combination with a key-operated locking-bolt; of recording mechanism and means for actuating it through the movement of the key, said mechanism including a key-indicator, and a recorder.

80

6. In a recording-lock, the combination with a key-operated locking-bolt; of recording mechanism and means for actuating it through the movement of the key, said mechanism including a key-indicator, a recorder, and a record-feed.

85

7. In a recording-lock, the combination with a key-operated locking-bolt; of recording mechanism including a key-indicator set by the key, an inker, a printing mechanism moved by the bolt, and paper-feeding mechanism also moved by the bolt.

90

8. In a recording-lock, the combination with a key-operated locking-bolt; of recording mechanism and means for actuating it through the movement of the key, said mechanism comprising time and key indicating dies side by side, an inker for them, a paper-feed for drawing a strip over them, a single platen above such strip, and means for operating the various elements when the bolt is moved by the key, substantially as described.

100

9. In a recording-lock, the combination with the bolt, and a cam thereon; of an indicator, means for moving it, a platen, an intermediate-pivoted arm supporting the latter, a push-bar pivoted to the other end of the arm and hanging therefrom normally over the smaller portion of said cam, and a stop for preventing the bar from swinging in the direction in which the cam moves to raise said bar, as and for the purpose set forth.

105

10. In a recording-lock, the combination with the bolt, and a cam thereon; of an indicator, means for moving it, a platen, and a bar connected with the platen and adapted to be struck by the cam when the bolt is moved, as and for the purpose set forth.

110

11. In a recording-lock, the combination with the bolt, and a pawl connected therewith; of an indicator, a platen, means for moving them, a paper-roll, a winding-drum therefor engaged by said pawl, and a retaining-pawl for the drum, as and for the purpose set forth.

115

12. In a recording-lock, the combination with the bolt adapted to be moved by keys having bits of several lengths, an indicator, printing mechanism coöperating therewith, and means for operating it; of a spring-retracted lever pivoted at one end and having

120

125

130

along its edge an active face merging into a neutral face around the keyhole for the purpose set forth, and connections between its other end and said indicator, substantially as described.

13. In a recording-lock, the combination with the bolt adapted to be moved by keys having bits of several lengths, an indicator, printing mechanism coöperating therewith, and means for operating it; of a spring-retracted lever pivoted at one end and having along its edge an active face merging into a

neutral face around the keyhole for the purpose set forth, a rack-bar pivoted to its other end, and a pinion on the hub of the indicator in mesh with said rack-bar, substantially as described.

In testimony whereof I have hereunto subscribed my signature this the 27th day of August, A. D. 1902.

ALLEN DE VILBISS, JR.
